UNITED STATES PATENT OFFICE.

ELI BROTHERS, OF LYNN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

METHOD OF MAKING SHOES.

Original application filed September 14, 1912, Serial No. 720,380. Divided and this application filed May 27, 1916. Serial No. 100,366. Renewed April 18 1923.

To all whom it may concern:

Be it known that I, ELI BROTHERS, a citizen of the United States, residing at Lynn, in the county of Essex and State of Massachusetts, have invented certain Improvements in Methods of Making Shoes, of which the following description, in connection with the accompanying drawings, is a specification, like reference characters on the drawings indicating like parts in the several figures.

This invention relates to methods of making shoes, the present application being a division of my earlier application Serial No. 720,380, filed on September 14, 1912, wherein is shown and claimed one form of apparatus by the aid of which the novel method may be practiced. The invention is applicable to the manufacture of various kinds of shoes, and the term "sole" as herein used is to be understood as applicable generically to the insole of a welt, McKay or other type of shoe as well as to the sole of a turn shoe, except where the context requires a more limited interpretation of the term.

An object of the invention is to provide a simple and convenient method whereby important economies in respect to time and labor may be effected in the manufacture of shoes. In one aspect of the invention, it is contemplated that the upper will be conformed to its last and held in finally lasted position with its margin free beyond the edge face of the sole. In accordance with the practice herein illustrated the upper is secured in conformity to its last with its margin projecting at the edge of the sole in substantially perpendicular relation to the plane of the sole, ready for an operation subsequent to the lasting, the character of which will depend upon the kind of shoe under treatment. In the manufacture of welt shoes, for example, it is within the province of the invention, in one of its aspects, to operate upon the shoe with the upper thus positioned to fasten a welt to the upper and insole. In the case of some kinds of shoes wherein the margin of the upper is drawn inwardly over the feather of the sole, including turn shoes and certain kinds of welt shoes, the overdrawing of the upper may in accordance with this invention be effected as an incident to an opera-

tion subsequent to lasting, thus dispensing with the usual overdrawing and temporary fastening of the margin of the upper as a part of the lasting of the shoe.

In a further aspect, the invention provides for controlling an upper in a novel manner after it has been conformed to its last and before it is fastened to the sole. In accordance with the practice herein illustrated the upper is secured in conformity to the last, while unattached to the sole, by a member applied about the shoe exteriorly of the periphery of the shoe bottom and portable with the shoe to permit the shoe to be manipulated in any way desired, the shoe with its upper thus held being subsequently transferred to a different position for the upper fastening operation. It is within the province of the invention thus to hold the upper in lasted position while presenting the shoe to an upper fastening machine, and further to utilize the upper holding member as a guide to determine the path of relative movement of the shoe and an instrumental for fastening the upper to the sole.

In still another aspect the invention has in view the working of an upper into conformity to its last by the aid of a device embracing the upper and the last round the forepart and adapted, for example, to conform itself more or less to the shape of the shoe and to engage the upper frictionally for a substantial distance heightwise of the shoe. In accordance with the practice illustrated such member is utilized subsequently to hold or secure the upper in conformity to its last and also to guide the shoe as hereinabove set forth in presenting the shoe to a machine for fastening the upper to the sole.

The invention may be further understood from the following description with the aid of the accompanying drawings and will then be more particularly pointed out in the claims.

Fig. 1 of the drawings shows an upper arranged on a last and the shoe embraced by a member such as shown in my earlier application by the aid of which the operator is wiping the upper upwardly about the forepart of the last.

Fig. 2 shows the upper wiped up and clamped around the forepart and sides of

the shoe at the edge of the last, this figure showing a last holding spindle and a toggle apparatus which may or may not be used to aid the operator in holding the shoe and 5 effecting the wiping.

Fig. 3 shows the upper as held clamped at the edge of the shoe bottom while the flange of the upper is being overlaid and permanently secured in proper relation to 10 a shoe sole or innersole, this figure illustrating the character of the upper fastening operation as applied to welt, turn or McKay shoes.

In practising the invention in the manner herein illustrated, a workman takes a last and arranges the upper thereon and embraces the shoe by a portable wiper and holder such as indicated at 2. This device may advantageously consist of a shoe 15 embracing member of resilient material and be constructed and arranged to adapt itself to the contour of the last and snugly fit the lateral surfaces of the last near the edge of the last bottom for a substantial distance 20 heightwise of the shoe, or downwardly from the bottom of an inverted shoe as seen in Figs. 2 and 3, while leaving the bottom surface of the last or the sole exposed, said member having separable rear ends yield- 25 ingly drawn together as claimed in said earlier application, and presenting an uninterrupted exterior face substantially parallel with the edge of the last around the toe and affording a continuous surface, as dis- 30 tinguished from the irregular surface of the shoe where the toe tip joins the vamp, by which the shoe can be guided, as shown in Fig. 3, in subsequently presenting it to receive the operation of machines which ordi- 35 narily guide by engagement with the shoe upper. If the upper has a back seam it should be properly located centrally on the back of the last where it will be retained, without tacking, by the action of the holder 40 and if the upper has a tip seam it can be made to come straight with little attention after the back seam is straight. The workman depresses the forepart of the shoe into the forepart of the embracing means 2, or 45 and if the upper has a tip seam it can be made to come straight with little attention after the back seam is straight. The workman depresses the forepart of the shoe into the forepart of the embracing means 2, or 50 swings up the forepart of said means while it pivots at its rear end on the heel end face of the shoe, the relative movement effecting a wiping and stretching of the upper upwardly to the edge of the last bottom, the 55 upper being conformed to the exterior or side faces of the last and the wiping means 2 resiliently adapting itself to the contour of the last and resiliently clamping the upper around the last and holding it in relation thereto to have its flange 3 permanently 60 secured to the sole. The latter may be put in place either before or after the upper is shaped and will vary in shape according to whether the shoe is to be of turn, welt, or 65 McKay construction. By reference to Fig.

2 it will be seen that as the upper is thus held or secured in lasted position by the clamp member and unattached to the sole, its margin is free beyond the edge face of the sole and projects in substantially perpendicular relation to the bottom face or the plane of the sole. 70

After the upper is shaped to the last as described it is contemplated that it will be carried to a mechanical fastening machine 75 as shown in Fig. 3, although obviously the upper might be fastened by stitches or tacks applied by hand. The upper is held continuously by the shaping means 2 in its

lasted relation to the last until it is permanently secured to the sole or innersole. The right hand portion of Fig. 3 illustrates the character of the upper fastening operation in the case of McKay shoes, and it will be evident that such fastening operation, which 80

as herein contemplated is independent of the lasting operation proper, may be performed by comparatively unskilled labor. At its left hand side Fig. 3 indicates the character of the upper fastening operation 85

as applied to turn shoes or to some kinds of welt shoes, an overdrawing of the margin of the upper being effected as an incident to the permanent stitching of the upper to the sole and, in the case of a welt shoe, to the attachment of the welt. In these different upper fastening operations the member 2, 90

it will be observed, is utilized to guide the shoe in its movement relatively to the fastening instrumentality, this being an advantage by reason of the fact that the clamp member presents a smooth outer surface adapted to guide the work with less friction than the upper materials and free from irregularities such as are presented, for ex- 95

ample, by the upper of a shoe at the tip seam. I may leave the upper materials unclamped immediately adjacent to the edge of the last bottom around the heel seat as indicated at 8. to facilitate certain, well-known systems of making heel seats, and I 100 may conform the upper to the shank of the shoe, particularly at the inner side of the shank, by a hinged section 9 of the shaping means. This has the advantage of laying the entire length of the shank into proper

relation to the last, and holding it for the securing operation which, effected step-by-step as usual, might otherwise not produce a proper distribution of the stock in a tight 105 shank. I may mount the last on a last spindle as indicated in Fig. 2, and in that case may or may not employ a toggle 12, 14, 18, 19, having a detachable connection 13 with the shaping means 2, to operate the 110

shaping means for wiping the upper upwardly around the forepart of the last. 115 While uppers have been conformed to lasts and overwiped at the toe and bound to a shoulder or rib on the tread face of a welt 120

125

or turn shoe innersol or sole and then transported to the fastening machine, it is new with me, as I am advised, to clamp or secure an upper in lasted relation to the side faces 5 of the forepart of a last below the tread face of the shoe and to hold the upper shaped to the last by said clamping means while carrying the shoe to a fastening machine and holding the upper for the fastening 10 operation. I desire to secure broad protection for securing an upper exteriorly with relation to the edge of the last bottom as distinguished from securing it within the boundaries of the last bottom independently 15 of how the upper is manipulated into conformity with the contour of the exterior or side faces of the last and independently of how the flange of the upper is manipulated into conformity with the contour of the tread face of the sole or inner sole inside 20 the edge of the last bottom.

Having explained the nature of this invention and described how it may be practised, I claim as new and desire to secure 25 by Letters Patent of the United States:—

1. That improvement in methods of making shoes which consists in assembling an upper on a last; inserting the shoe within a portable lasting device which is constructed 30 and arranged to embrace the forepart of the shoe and to adapt itself to and contact with substantially the entire periphery of the fore part; relatively turning the lasting device and the shoe to wipe the upper over 35 the side and end faces of the forepart of the last to the edge of the last bottom; and subjecting the shoe, with the portable lasting device holding the upper in lasted position, to an upper and sole connecting operation. 40

2. That improvement in methods of making shoes which comprises arranging an upper on a last, embracing the shoe by means constructed and arranged to contact with an appreciable portion of the vertical contour 45 of the forepart and wiping the upper of the forepart of the shoe upwardly into conformation with the exterior faces of the forepart of the last to the edge of the last bottom, and clamping the upper exteriorly 50 around the forepart of the last and holding it while the shoe is subjected to an operation for connecting the flange of the upper around the forepart of the shoe in proper 55 relation to a sole applied to the bottom face of the last.

3. That improvement in methods of making shoes which comprises arranging an upper on a last, embracing the inverted shoe around the forepart by means contacting with the upper for a substantial distance and below the bottom face of the last at 60 the toe, relatively moving the last and the embracing means to wipe the upper upwardly into conformation with the contour of the

side faces of the forepart of the last and clamping the upper exteriorly with relation to the edge of the last bottom by the wiping means, and then maintaining the shoe and the wiping means in operative relationship 70 while connecting the flange of the upper to a sole inside the edge of the shoe bottom.

4. That improvement in methods of making shoes which comprises assembling the upper materials and the last, manipulating the upper into lasted relation to the side faces of the forepart of the last and binding the upper to the last around the toe exteriorly of the edge of the shoe bottom, by means which engages the upper for a substantial distance heightwise of the shoe and is capable of unrestricted movement with the shoe, interrupting the procedure for an indefinite period, and thereafter manipulating the margin of the upper into 80 position to be secured to the margin of a sole and securing it. 85

5. That improvement in methods of making shoes which comprises manipulating an upper into lasted position around the forepart of a last, and holding the upper by a portable forepart embracing means which is adapted for attachment to the shoe exteriorly of the edge of the shoe bottom, removing the shoe with said embracing means holding the upper to a different location, and thereafter working the flange of the upper over the margin of a sole and securing it and then removing said holding means. 90 95

6. That improvement in methods of making shoes which comprises applying to an assembled shoe a portable forepart embracing means which is adapted for engagement with a substantial portion of the contour of the shoe from the edge of the shoe bottom 100 downwardly and for being fastened to the shoe and turning the shoe and said means relatively for wiping the upper stock over the curved contour of the toe upwardly to the edge of the shoe bottom, maintaining the upper in that position by said means, and laying the flange of the upper over the margin of a sole and securing it. 105 110

7. That improvement in methods of making shoes which comprises manipulating an upper into lasted relation to the side faces of the forepart of a last and clamping or binding the upper below the sole receiving face of the last by a portable holding means to maintain it in lasted relation to the side faces of the forepart of the last, removing the shoe to a different location with the upper so held and its margin unsecured, thereafter securing the upper to a sole and then removing the portable holding means. 115 120 125

8. That improvement in methods of making shoes which consists in assembling an upper on a last, stretching the upper into substantial conformity with the contour of the side faces of the last, and securing the 130

upper exteriorly with relation to the edge of the last bottom in conformed relation to the side faces of the last by a portable holding device effecting substantially continuous engagement with the upper around the toe and presenting an uninterrupted exterior face substantially parallel with the edge of the last bottom around the toe and affording a surface by which the shoe can be guided 10 in subsequently presenting the shoe to an upper and sole connecting machine.

9. That improvement in methods of making shoes which comprises assembling an upper and sole on a last and manipulating 15 the upper into lasted relation to the side faces of the forepart of the last adjacent to the edge of the sole and clamping or binding the upper below the outer face of the sole by a portable holding means to maintain 20 it in lasted relation, removing the shoe to a different location with the upper so held and its margin unsecured and thereafter securing the upper to the sole and then removing the portable holding means.

25 10. That improvement in the art of lasting welt shoes which consists in causing the edge of an upper adjacent the edge face of an insole to stand substantially at right angles to the face of the insole, and securing 30 the upper in that position.

11. That improvement in methods of making welt shoes which consists in conforming an upper to a last and securing the upper for the welt attaching operation with the margin of the upper upstanding at the edge of the insole substantially at right angles to the plane of the insole, and then proceeding to operate on the shoe to fasten a welt to the upper and insole.

40 12. That improvement in methods of making welt shoes which consists in assembling on a last an upper and also an insole of substantially the same dimensions as the bottom face of the last, conforming the upper to

the last and securing it with its margin free 45 beyond the edge face of the insole and operating on the shoe in that condition to fasten the upper and a welt simultaneously to the insole.

13. That improvement in methods of making shoes which consists in assembling on a last an upper and a channeled sole, conforming the upper to the last and securing it in its conformed relation, unattached to the sole, with its margin projecting freely beyond the edge face of the sole, and operating upon the shoe in that condition to draw the margin of the upper inwardly and fasten it permanently to the sole by the final upper and sole connecting stitches extending into 60 the channel of the sole.

65 14. That improvement in methods of making shoes which consists in working an upper into conformity to the contour of a last and positioning it with its margin projecting freely beyond the edge face of the sole of the shoe, securing the upper in that position by a member extending round the toe exteriorly of the periphery of the shoe bottom, and thereafter utilizing said member as a 70 guide to determine the path of relative movement of the shoe and an instrumentality for fastening the upper to the sole.

75 15. That improvement in methods of making shoes which consists in assembling an upper and a sole on a last, conforming the upper to the last and securing it in its conformed relation, unattached to the sole, by a holding member applied exteriorly of the periphery of the shoe bottom and portable 80 with the shoe, presenting the shoe in that condition to the operation of a machine for fastening the upper to the sole, and thereafter removing said holding member.

In testimony whereof I have signed my name to this specification.

ELI BROTHERS.
